CLAY TESTING APPARATUS

David H. Rowland, Baltimore, Md., assignor to
 Locke Insulator Corporation, Baltimore, Md.,
 a corporation of Maryland

Application December 20, 1932, Serial No. 648,114

4 Claims. (Cl. 265—14)

The invention relates to the determination of the plasticity of clay intended for the production of ceramic ware, such for instance as porcelain insulators or the like, though not confined to such use, and has for its general object the provision of an apparatus whereby sample chunks or billets of clay taken from a pug mill may be readily tested as to plasticity or stiffness.

It is well known that the efficiency of pug mills and plunging machines for shaping insulators and other porcelain ware depends to a great extent upon the hardness of the clay which is furnished to them. Variations in this factor will greatly affect the uniformity of the product as regards shrinkage and drying losses. It is consequently of great importance to have complete knowledge of the condition of the clay so that it will be possible to supervise the filter presses which perform part of the preliminary clay treatment so as to obtain a much more uniform product. It is with these facts in view that I have devised the present invention which has for an important object the provision of a machine into which may be placed at appropriate intervals sample chunks or billets taken from the preliminary pug mill, the machine embodying means for making a record of the hardness of the clay so that by this means an almost continuous recording may be brought about so that the attendants will be at all times apprised of conditions and may make whatever changes, if any, are needed in the treating steps.

Another object of the invention is to provide a machine for this purpose by means of which a pressure may be applied to a succession of sample chunks of uniform size and the resulting pressure which is transmitted through the chunks is recorded as a measure of the extent of compression, flattening or distortion of the chunks.

A more specific object is to provide a machine of this character which is power operated and which will automatically stop after a force has been applied to a suitable chunk of material to be tested so that the conditions for all may be made the same.

An additional object is to provide a device for this purpose which will be simple and inexpensive to make, easy to assemble, use and control, positive in action, efficient and durable in service, and a general improvement in the art.

To the attainment of the foregoing and other objects and advantages, the invention preferably consists in the details of construction and the arrangement and combination of parts to be hereinafter more fully described and claimed, and

illustrated in the accompanying drawings in which:

Figure 1 is a front elevation of a machine constructed in accordance with the invention,

Figure 2 is an elevation taken at right angles to Figure 1,

Figure 3 is a fragmentary plan view with the recorder omitted,

Figure 4 is a detail section through a valve mechanism forming part of the device.

Referring more particularly to the drawings I have shown the device as comprising an appropriate stationary support here represented as including a base 10 from which rise standards 11 and 12, the former terminating at its upper end in a bearing 13 and the latter being formed with a bearing 14. Journalled through these bearings is a shaft 15 adapted to be driven by means to be described and provided with a crank or eccentric portion 15a engaged within a pitman 16.

Near its upper end the standard 12 is provided with bearings 17 and 18 and at its intermediate portion with other bearings 19 and 20, the bearings 17, 18, 19 and 20 being in vertical alinement or axial relation. Mounted within the bearing 18 is a rod 21 provided at its lower end with a disk 22 which may be described as constituting an anvil. The rod 21 is slidable through the bearing 18 and has its upper end appropriately connected with a member 23 depending from or adapted to react against the underside of a wafer 24 which, as is known in the art, ordinarily comprises a pair of diaphragms connected at their edges and defining a compressible chamber. It is intended that this wafer contain liquid under a certain predetermined pressure, the interior communicating through a tube 25 with a register or recorder indicated at 26. No details of this device are given for the reason that such of the pressure operated type are common and well known in the art involving systems where the degree of pressure need be known.

The actual details regarding the connection of the wafer with the register or recorder are probably more or less immaterial. Nevertheless I have shown a bushing 27 fitting within the lower end of the bearing 17 and abutting against the top of the wafer, a vertically elongated body 28 being suitably secured, as by screwing, axially through this bushing. The body is represented as having an enlarged intermediate portion 29 providing a shorter bearing on a washer 30 engaged against the top of the bearing member 17. The body 28 is disclosed as having a central or axial passage 31 communicating with the inter-

rior of the wafer and with a slightly enlarged chamber 32 at the upper end of the body, a transverse port 33 being provided in the enlarged portion 29 and intersecting the passage 31. The 5 above mentioned tube 25 is fastened in the port 33. It is desirable that the liquid in the system be placed under appropriate pressure and for this reason the upper end of the body 28 is shown as having a reduced externally threaded portion 34 onto which may be screwed the nipple of a suitable compression pump. Located within the chamber 32 and secured within the upper end portion 34 is a valve assembly indicated as a whole by the numeral 35 but not described in 10 detail as it may be identically the same as the well known "Schroeder" valve used in the inflation stems or tubes of pneumatic tires and the like. By connecting the pump to the threaded extension 34 liquid may be introduced into the 15 recording and wafer system and placed under any desired pressure.

Slidable through the bearings 19 and 20 is a vertically movable rod or plunger 36 equipped at its upper end with a head 37 upon which is intended to be placed the sample of clay to be tested. At its lower end the plunger 36 is represented as forked and pivotally connected at 38 with the pitman 16 on the shaft 15.

The means for rotating the shaft 15 whereby the resultant movement of the crank arm will reciprocate the plunger 36, is here represented as comprising a worm wheel 39 carried by the shaft 15 and meshing with a worm 40 on the shaft 41 of an electric motor 42 mounted on supports 43 rising from the base 18. Obviously when the motor is energized the rotation of the worm 40 will cause the worm wheel 39 to be rotated.

In order that the extent of rotation of the 40 shaft 15, and consequently the upward movement of the plunger 36, may be automatically controlled or made uniform for every test, I provide an automatic circuit breaker for the motor circuit here represented as comprising a 45 stationary contact 44 and a flexible movable contact 45 carried by a bracket 46 and insulated therefrom and from each other as by blocks 47. The contact 45 is normally divergent with respect to the contact 44 and carries a projection 50 48 engaged by the periphery of a disk 49 secured on the shaft 15, this engagement maintaining the contact 45 in engagement with the contact 44 so that the motor circuit will be complete. However, the disk 49 is formed with a notch 50 which 55 the projection 48 is adapted to enter, after the shaft 15 has made one complete revolution and the plunger 36 has completed its upward stroke, the arrangement being clearly such that when the projection enters the recess or notch the 60 contact 45 will spring away from the contact 44 and open the motor circuit.

In the use of the device, assuming that the plunger 36 is at the lowermost limit of its movement, the operator places upon the plunger head 65 37 the sample of clay to be tested. The operator then moves the contact 45 manually into engagement with the contact 44 as shown in Figure 2 for closing the motor circuit. The rotation of the motor shaft 41 and worm 40 thereon will then cause rotation of the worm wheel 39, shaft 15 and disk 49. Just as soon as the disk moves a slight part of a turn its edge will engage the projection 48 and maintain the contact 45 in engagement with the contact 44 until the shaft

can make a complete turn and the notch 50 again registers with the projection 48. As the shaft 15 rotates the eccentrically driven pitman 16 will move upwardly, thereby forcing the plunger 36 and head 37 upwardly and compressing the clay sample against the disk 22 which, together with the rod 21, will be forced upwardly and apply pressure to the wafer 24. The consequent compression of the wafer will cause the liquid in the recording system to operate the recorder 26 in a well known manner. Of course the plunger 36 is moved upwardly to its maximum extent during the first half revolution of the shaft 15 and then recedes from the disk 22 during the latter half of the revolution so that when one rotation of the shaft has been completed the parts will be all restored to their initial position ready for testing the next clay sample or specimen. In the actual carrying out of a testing system embodying the use of my device test pieces or chunks of uniform size are taken from the pug mill at frequent intervals and the test made with regularity and with sufficient frequency to obtain a practically continuous reading on the recorder. The plasticity or the stiffness or hardness of the clay may thus be determined at any time so that the attendant in charge may know what conditions are and whether or not any changes should be made in the preliminary treatment of the clay.

From the foregoing description and a study of the drawings it will be apparent that I have thus provided a very simple and inexpensive machine for the purpose specified which will greatly facilitate the maintenance of efficiency in the preparation and handling of clay intended for use in the manufacture of ceramic ware. It is believed that the construction, operation and advantages will be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A machine for testing the plasticity of a sample of material, comprising axially arranged slidably mounted relatively movable members carrying heads adapted to have the sample interposed between them for compression thereby, a compressible wafer containing fluid under pressure and arranged for compression by longitudinal movement of one of said members, a pressure gauge connected with said wafer, there being a check valved passage communicating with said wafer enabling fluid under selected pressure to be introduced within the wafer, a shaft arranged at right angles to the axis of said members and having a crank, a pitman revolvably engaged within the crank and pivotally connected with the other of said members, an electric motor for rotating said shaft, a circuit breaker interposed in the motor circuit, and means operated by rotation of said shaft for breaking the circuit when the shaft has made one complete revolution.

2. A machine for testing the plasticity of a sample of material, comprising a base, an upright rising from the base and provided with a plurality

of laterally extending arms, upper and lower axially arranged members slidable through certain of said arms and movable relatively, heads on the adjacent ends of said members adapted to have the sample interposed between them for compression thereby, a compressible wafer mounted beneath the uppermost arm, a gauge connected with said wafer, said wafer being compressingly engaged by the upper end of the upper 10 slidable member, bearings carried by the base, a horizontal shaft journaled through said bearings and formed with a crank, a pitman connected with said crank and pivotally connected with the lower end of the lower slidable member, an electric motor mounted on the base and having a gear 15 connection with said shaft, a circuit breaker mounted on the base and including a fixed contact and a movable spring contact equipped with a projection, and a disk carried by and rotatable 20 with said shaft and having a notch in its periphery for receiving said projection and thereby breaking the motor circuit when said shaft has made a complete revolution.

3. A machine for testing the plasticity of a sample of material, comprising axially arranged slidably mounted relatively movable members carrying heads adapted to have the sample interposed between them for compression thereby, means for moving said members relatively, 25 a compressible wafer engageable by one of said members for compression thereby, a body member in engagement with said wafer and having a

longitudinal bore communicating with the interior thereof and having a counterbore defining a valve seat and further having a lateral passage located between the valve seat and the wafer, a pressure gauge connected with said lateral passage for indicating the pressure within the wafer, and an inwardly opening spring pressed check valve normally closing said valve seat and openable upon the application of fluid pressure through said bore into the wafer whereby the 10 initial pressure within the latter may be varied.

4. A machine for testing the plasticity of a sample of material, comprising axially arranged slidably mounted relatively movable members carrying heads adapted to have the sample interposed between them for compression thereby, a compressible wafer containing fluid under pressure arranged for compression by longitudinal movement of one of said members, there being a bore communicating with said wafer, a check 15 valve located within said bore whereby fluid under a selected pressure may be introduced within the wafer, a pressure gage, a connection between the pressure gage and said bore between said check 20 valve and the wafer, rotary means connected with the other of said members for moving the same longitudinally with respect to the first named member, and means for automatically stopping the movement of said rotary means after one 25 revolution thereof.

DAVIDGE H. ROWLAND.
